UNITED STATES PATENT OFFICE.

JEROME B. FELLOWS, OF BOSTON, MASSACHUSETTS, ASSIGNOR OF ONE-HALF TO
CHARLES F. LIBBY, OF PORTLAND, MAINE.

LAWN-SPRINKLER.

1,011,934.

Specification of Letters Patent. Patented Dec. 19, 1911.

Application filed October 11, 1909. Serial No. 522,180.

To all whom it may concern:

Be it known that I, JEROME B. FELLOWS, a citizen of the United States of America, and resident of Boston, in the county of 5 Suffolk and State of Massachusetts, have invented certain new and useful Improvements in Lawn-Sprinklers, of which the following is a full, clear, and exact description.

This invention relates to improvements in 10 water sprinklers to be used especially on lawns, of a kind in which are comprised a plurality of differently directed and revolvable water delivery members, such as nozzles or sprinklers, and means operable by the 15 water supplied to the apparatus by a hose, and which passes to and through the delivery members for causing the revolvable movements of the latter.

The objects of the invention are to provide 20 a sprinkling apparatus having revolvable delivery members which are so adjustable that one stream or spray may be thrown in a wide circular distribution to cover a large area while another stream or spray 25 may be thrown for circular distribution in a smaller area and within that covered by the first delivery member; and to provide a sprinkling apparatus constituted by parts which by the construction and arrangement 30 thereof renders the sprinkler certainly operative irrespective of the variations in the directions in which the streams or sprays are thrown.

Other objects for the attainment of advantages and the general efficiency of the 35 sprinkler are acquired in and by the organization of the operative parts of the apparatus as will be hereinafter rendered manifest.

The invention consists, in a sprinkler, in the combination and arrangement of parts 40 and the constructions of certain of the parts substantially as hereinafter described in conjunction with the accompanying drawings 45 and set forth in the claim.

In the drawings:—Figure 1 is a plan view of the improved apparatus with the delivery members or sprinklers thereof shown as in one of the extremes of the positions in which

they may be adjusted. Fig. 2 is a plan view 50 of the body or casing of the sprinkler with the cap or cover and parts carried thereby removed. Fig. 3 is a vertical sectional view as taken on line 3—3, Fig. 1. Fig. 4 is a view showing an interchangeable nozzle on 55 one of the delivery members instead of a sprinkler.

Similar characters of reference indicate corresponding parts in all of the views.

In the drawings, A represents the body 60 of the apparatus, the same comprising a casing of a general cylindrical shape having a comparatively slight dimension in the direction of its axis. The casing is provided at one side with a hub a for receiving a 65 coupling connection therewith of a hose, the passage a² through such part being tangential to the circular wall of the casing. The casing is made with a cap b or cover, which is held tightly in place by the screws 10, 70 the shanks of which enter lugs 12 internally provided near the upper edge of the casing. A suitable packing may be provided between the cap and body of the casing for making the closure absolutely tight. The water outlet conduit comprises a pipe B which extends upwardly from communication with the interior of the casing at the top thereof and is provided with branches d d on which are rotatively adjustable water delivery 80 members C C which may comprise or are equipped either with sprinklers as shown at e or with nozzles e², as represented in Fig. 4.

In order to constitute an efficient bearing for the rotative upstanding pipe B, the cap 85 of the casing is made with a tubular vertical extension f having external screw threads g at its upper end portion and provided with an internal shoulder h just below its upper end; and the pipe B has the lower 90 portion thereof located within said tubular extension f, its end extending slightly below the top of the cap and into the chamber in the casing; and said pipe B has an external flange i which has a bearing support on the 95 aforesaid internal flange of the upstanding tubular part f; and the coupling ring j, the internal flange j² of which encircles the pipe

B by the internal screw threads on its body, has a screw engagement with the threads on the upper end portion of the tubular extension f, and a packing j² is interposed between the internal flange j² of the coupling ring and the upper end of the tubular extension f, a water-tight connection being thus made.

The motor, which is driven by the water entering and passing through the casing, comprises, as shown, an axially vertical water wheel D made with a central hub k' with a surrounding frame k² and with radial blades k, the widths or vertical dimensions of which are nearly as great as the vertical space within the hollow circular body A. The said water wheel D is provided with an arbor or center shaft k³ which is made as one with the wheel, such shaft having journal bearings in sockets therefor in the base and cap of the casing. The said arbor is provided with a fixed pinion m near its upper end, but slightly below the under surface of the cap B, with which meshes a spur gear wheel m² on a stud m' depending a short distance below the cap, said spur gear having made as one and concentrically therewith a pinion m³ which is in mesh with a spur gear wheel m⁴ affixed on the lower end of the pipe B which protrudes slightly below the under surface of the cap.

The opposite obliquely upwardly arranged branches d d of the pipe B are, as shown, arranged at angles of 45 degrees to the axis of the pipe; and the water delivery members C C which are coupled to said oblique branches by the coupling rings n n have their portions 14, by which they are coupled, angular to their outer portions 15,—the portions 14 and 15 of the water delivery members being also here shown as at angles of 45 degrees to each other. The coupling rings n while having the capability of making water tight connections between the delivery members C and the branches d of the pipe B also constitute means for permitting revoluble adjustments of the water delivery members relatively to the pipe branches and for tensioning or confining such members in their individually adjusted positions. With a hose for supplying water connected by the coupling rings a², the water will sidewise and more or less tangentially enter the casing and drive the water wheel around; the water wheel constitutes a motor, which, through the gearing, imparts a slow steady rotary motion to the upstanding pipe B which is the conduit through which all of the water, entering the casing, and driving the water wheel passes; and the water will, in passing through the delivery members, be thrown in different lines laterally related to the axis of the outlet pipe. Each water delivery member C may have an adjustment

so that the line of delivery is horizontal and at right angles to the axis of the pipe or vertically in lines parallel with, and offside from, the axis of the pipe, or obliquely upwardly at an angle of any degree between horizontal and vertical lines; and with nozzle or sprinkler ends directed either forwardly or rearwardly relatively to the direction of rotary movement of the water outlet pipe by which they are carried. The delivery members may be adjusted in positions to have corresponding angles so that the stream or spray of both will be correspondingly projected, or one may be arranged for throwing outwardly in a maximum or considerable degree while the other delivery may be arranged for throwing a stream or spray within a circular area circumscribed by that covered by the given first delivery member; and one of the delivery members C may be employed as, or equipped with, a nozzle, while the other may be equipped with a sprinkler head. In short, the adjustments and relative arrangements of the delivery members may be so varied and many that while too numerous to herein mention, it will be appreciated that they constitute very valuable and attractive capabilities in the sprinkler apparatus; and it may be furthermore stated that in this sprinkler irrespective of how the delivery members may be relatively adjusted, and even if they are set in such opposition that the reaction or back pressure of the stream passing from one might be diametrically opposite the reaction of the stream passing through the other, there can be no deadlocking or rendering of the sprinkler inoperative, as has been the case in certain other sprinklers relying upon the reaction or back pressure of the water for insuring the revoluble movements of the sprinklers or nozzles, because in the present apparatus the motor which is positively driven by all the water passing through the casing rotatively drives, with certainty, the outlet pipe B by which the water delivery members are revolubly carried.

I claim:—

In a water sprinkler, in combination, a casing having a sidewise opening water inlet passage, having at its top a tubular vertical extension externally screw threaded and provided with an internal shoulder below its upper end, a pipe, the lower portion of which is located within said tubular extension, its lower end being located within the casing while a portion thereof within and near the top of said tubular extension has an external flange having a bearing support on the aforesaid internal flange, a coupling ring provided with an internal flange externally encircling said pipe and said ring screw engaging the threads of said tubular

extension, said pipe having upwardly oblique branches at its upper end and water delivery members, the inner end portions of which are coupled to said branches and are 5 angular to the outer end portions of said members, a motor in the casing rotatively operable by the water entering the latter, and driving connections between said motor

and the lower end of said pipe which protrudes into the upper portion of the casing. 10
Signed by me at Boston, Mass., in presence of two subscribing witnesses.
